(57) **CLAIM**

The ornamental design for a roofing tile of metal incorporating panel of photovoltaic cells, as shown and described.

DESCRIPTION

FIG. 1 is a perspective view of a roofing tile of metal incorporating panel of photovoltaic cells of our new design; FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

1 Claim, 6 Drawing Sheets

FIG. 1

FIG. 2

FIG. 3

FIG. 4

FIG. 5

FIG. 6

FIG. 7
